UNITED STATES PATENT OFFICE

2,146,879

APPARATUS FOR BREAKING MATERIAL

Frank Hall Armstrong, Michigan City, Ind., assignor, by mesne assignments, to Cardox Corporation, a corporation of Illinois

Application September 24, 1935, Serial No. 41,863

5 Claims. (CL. 102—5)

This invention relates to methods of and apparatus for breaking material, and more particularly to improvements in methods of and apparatus for breaking down coal or similar materials in mines.

An object of the invention is to provide an improved method of and apparatus for breaking down coal from the coal face in a coal mine. Another object is to provide an improved material breaking apparatus of the type wherein highly compressed air is employed as a material breaking medium and having improved means for effecting discharge of the compressed air when the breaking apparatus is suitably positioned in a drill hole in the material to be broken. Yet another object is to provide an improved material breaking apparatus wherein a semi-portable air compressor located at a point remote from the coal face is employed for supplying high pressure air through long lines of tubing to the material breaking devices located in drill holes in the coal seam, and having associated therewith improved control means located relatively near the coal face at a point remote from the compressor, whereby the supply of air to the material breaking device and the discharge of air from the latter to effect charge release, may be readily controlled. A still further object is to provide a novel system for breaking down material in mines. These and other objects will, however, herein-after more fully appear.

In the accompanying drawings there is shown for purposes of illustration one form which the invention may assume in practice.

In these drawings:

Fig. 1 is a vertical sectional view through a portion of a mine showing an air breaking device in position in a drill hole in the coal seam, the remote control valve, the compressor in the cross cut, and the tubing extending between the compressor control valves and the air breaking device.

Fig. 2 is a sectional view of the control valves.

Fig. 3 is a view similar to Fig. 2 showing the valves in a different position.

Fig. 4 is a diagrammatic plan view showing a mine equipped with the illustrative form of the improved air breaking system.

In this illustrative construction 1 indicates an air compressor of the semi-portable high pressure type, located in its station formed in one of alternate cross-cuts in the chain pillar of the mine, so that several rooms can be supplied with high pressure air through long lines of tubing 2 located in alternate rooms. In this instance, the

air compressor is shown in position to supply air pressure to a plurality of rooms, herein eight in number, the rooms, in Fig. 4, indicated at A, B, C, D, E, F, G, and H. The parallel mine entries are indicated at I and J, and K indicates the cross-cuts in the chain pillar between the mine entries. In room A, a drill 3 is shown in drilling position for drilling the holes for receiving the air breaking devices. Rooms B, D and E are shown with the coal face drilled ready for shooting, while room H shows a coal cutting machine 4 making an undercut across the coal face. Rooms C and F show the coal face broken down ready for loading, while room G shows an air breaking device in position in a drill hole ready for breaking down the coal. Located in breakthroughs L between alternate rooms are the improved remote control valves, generally designated 5.

As shown most clearly in Fig. 1, the air breaking devices are each in the form of an air shell 6 arranged in a drill hole 7 drilled in the coal seam above an undercut kerf 8 formed by the coal cutting machine 4. The drill hole at the outer end of the hole is preferably tamped at 9. The air shell may be of the type similar to that disclosed in my copending application Serial No. 18,579, filed April 27, 1935, which has matured into Patent No. 2,083,548, dated June 15, 1937, wherein a differential valve mechanism is employed for controlling the release of the coal breaking charge from the air shell, and embodying a control piston mounted in a control chamber. The control piston is held in valve closing position by the pressure in the shell and opens automatically the valve to release the charge of air pressure when the control chamber is vented to atmosphere. As the detailed construction of the shell does not per se enter into this invention, further description thereof is considered unnecessary.

Now referring to the improved remote control valves 5, one of which is shown in Figs. 2 and 3, it will be noted that a casing 10 has end bores 11 and 12 connected by an axial passage 13. Threaded within the bore 11 is a plug 14 in turn having a bore 15 in which a stem 16 of a double-ended control valve 17 is slidably guided. A stuffing box 18 seals tightly against the periphery of the valve stem to prevent leakage past the stem, and a gland nut 19 is provided for maintaining the packing in tight sealing relation. Threaded in the bore 12 is a plug 20 having a bore 21 in which is threaded a screw 22 having a polygonal operating portion 23.

This screw is formed integral with the valve 17. The plug 14 is formed with an axial chamber 24 surrounded at the inner face of the plug by an annular valve seat 25, while the plug 20 is formed in an axial chamber 26 surrounded at the inner face of the plug by an annular valve seat 27. Threadedly connected at 28 and 29, respectively within the opposite sides of the casing, is the tubing 2 leading from the air compressor to the air shell. The end of the bore 11 and the adjacent end of the plug 14 are grooved to form an annular recess 30 and a passage 31 connects this recess with the tubing 2, while passage 32 connects this recess with the chamber 24. The plug 20 is sealed tightly against a gasket 33 against the end wall of the bore 12, and formed in the wall of the bore surrounding the inner portion of the plug 20, is an annular recess 34 connected by passage 35 to atmosphere. Passage 36 connects the chamber 26 with the recess 34. When the valve 17 is in the position shown in Fig. 2, air under high pressure may flow from the air compressor through the tubing 2 to the air shell. The air pressure from the compressor flowing through passage 31, recess 30, passage 32 through the axial chamber 25, axial passage 13 to the air shell, while communication of the axial passage 13 with the vent passage 35 is cut off by the valve seated against the seat 27. When the adjusting screw 22 is adjusted axially to move the valve into the position shown in Fig. 3, the air shell control chamber is vented to atmosphere through axial passage 13, axial chamber 26, passages 36, groove 34, and vent passage 35, while the supply of air pressure from the compressor to the shell is cut off by the valve seating tightly against the seat 25, thereby cutting off communication of the chamber 24 with the axial passage 13.

In this improved material breaking system the air compressor is preferably located at a remote point from the coal face in the compressor station K while the control valves are located in the break-throughs L formed in the pillars of the alternate rooms and substantially a thousand feet of tubing extend between these control valves 5 and the compressor, while only substantially fifty feet of tubing extend between the valves 5 and the air shells. It will be noted that the long lengths of tubing between the control valves 5 and the compressor always contain high pressure air, so that when it is desired to operate the air shells, it is unnecessary for the compressor to pump up a high pressure in long lines of tubing and as a result, the time consumed in loading the shells is greatly reduced. The control valves are located at a safe point for the operator in the break-throughs relatively close to the coal face so that the operator may readily control the release of the air charges into the drill holes. It will further be evident that by the provision of the improved material breaking system, it is possible for a single compressor, located at a remote point, to supply air pressure to the air shells in a number of rooms, the air compressor being located away from the congested area at the working face. Other uses and advantages of the improved method of and apparatus for breaking material will be clearly apparent to those skilled in the art.

While there is in this application specifically described one form which the invention may assume in practice, it will be understood that this form of the same is shown for purposes of illustration and that the invention may be modified and embodied in various other forms without

departing from its spirit or the scope of the appended claims.

What I claim as new and desire to secure by Letters Patent is:

1. Means for breaking coal in mines comprising an air shell adapted to be inserted in each of a plurality of drill holes formed in the coal seam in different mine rooms, each air shell including discharge mechanism operable by a differential fluid pressure condition created thereby by venting from the shell to the atmosphere a fraction of the total shell charge, a source of compressed air located at a station removed from principal traffic lanes and remote from the coal face, long lines of tubing connecting the several shells to the source of compressed air with each of said lines extending through at least one break-through connection between adjacent rooms and located close to the coal faces being worked upon, and means in the portions of the lines of tubing located in said break-throughs for effecting fluid flow through the long lines of tubing from the source to the several shells until the pressures of the charges in the several shells reach desired values and for stopping fluid flow and venting to the atmosphere for any particular shell the differential pressure creating fraction of the shell charge and the air from the section of tubing extending between the said means and the shell being actuated to effect operation of the shell discharge mechanism.

2. In an air shooting apparatus, a source of pressure supply, a blasting shell adapted to be positioned in a drill hole remotely located with respect to said source and operable to release its pressure charge upon venting of a portion of the pressure charge, a casing having end bores and an intermediate passage, a bored plug detachably mounted in each casing end bore and providing at one end of its bore a valve seat presented to an end of said intermediate passage, a passage between the bore of one plug and the atmosphere, a tubing connection communicating with the intermediate passage of the casing, a line of tubing of considerable length connected to the source of pressure supply and said tubing connection passage, a second tubing connection passage communicating with the bore of the other plug, a line of tubing of less length than the first mentioned line connected to the shell and the second tubing connection passage, and a reciprocal valve body positioned in said intermediate passage of the casing and movable to alternately engage the valve seats provided by said plugs to selectively effect communication between the source of supply and the shell and to interrupt such communication and vent to the atmosphere the shorter line of tubing and said portion of pressure charge from the shell.

3. In an air shooting apparatus, a source of pressure supply, a shell remotely located with respect to the source of supply and operable to release its pressure charge upon venting of a portion of the pressure charge, tubing of substantial length leading from the supply to the shell and extending through at least one break-through connection between adjacent mine rooms which is located closer to the coal face being worked upon than the source of pressure supply, and a control device connected in the portion of the tubing which extends through said break-through connection and being operable selectively to effect communication between the supply and the shell and to interrupt such communication and vent the portion of the tubing leading from the shell to the control device.

4. Means for breaking coal in mines comprising an air shell adapted to be inserted in a drill hole formed in the coal seam, said shell including discharge mechanism operable by a differential fluid pressure condition created thereby by venting from the shell to the atmosphere a portion of the total shell charge, a source of compressed air located at a station removed from principal traffic lanes and remote from the coal face, a long line of tubing connecting the shell to the source of compressed air and extending through at least one break-through connection between adjacent rooms and located close to the coal face being worked upon, and means in the portion of the line of tubing located in said break-through for effecting fluid flow through the long line of tubing from the source of supply to the shell until the pressure of the charge in the shell reaches a desired value and for stopping fluid flow and venting to the atmosphere the differential pressure creating fraction of the shell charge and the air from the section of tubing extending between the said means and the shell to effect operation of the shell discharge mechanism.

25

5. In a air shooting apparatus, a source of pressure supply, a blasting shell adapted to be positioned in a drill hole remotely located with respect to said source and operable to release its pressure charge upon venting of a portion of the pressure charge, a valve casing having a bore and a plurality of chambers arranged in alignment, a line of tubing of considerable length connected to the source of pressure supply and one of said casing chambers, a vent passage communicating with the other of the casing chambers, a line of tubing of less length than the first mentioned line connected to the shell and the casing bore, and a reciprocating valve body positioned in said casing bore and movable to alternately effect communication between the casing bore to which the shell tubing is connected and the casing chamber to which the source of supply is connected and to interrupt said communication and connect the chamber having the vent passage to the casing bore so as to vent the shorter line of tubing and said portion of pressure charge from the shell.
